United States Patent Office.

LOVIAS D. TOWSLEY, OF NEWARK, NEW JERSEY.

Letters Patent No. 98,208, dated December 21, 1869.

IMPROVED SELF-VENTILATING SAFETY-CAN FOR FILLING AND DISCHARGING HYDROCARBON-APPARATUS.

The Schedule referred to in these Letters Patent and making part of the same.

To all whom it may concern:

Be it known that I, LOVIAS D. TOWSLEY, of Newark, in the county of Essex, and State of New Jersey, have invented certain new and useful Improvements in Self-Ventilating Safety-cans for Filling and Discharging Hydrocarbon-Apparatus; and I do hereby declare that the following is a full, clear, and exact description thereof, reference being had to the accompanying drawings, which make part of the same, and in which—

Figure 1 represents a vertical longitudinal section of a self-ventilating safety-can, embracing my improvements.

The invention, in the construction of my can, consists in the arrangement of a tube therewith, in such manner that one of its ends will be in direct communication with the opening through which the vessel is filled with the fluid, while its other end is in direct communication with the opening through which the fluid is discharged from the vessel; that is to say, the openings of said tube maintain relatively such a position with respect to the openings of the can, as that the fluid passing into or out of the vessel, shall be greatly hastened in its passage, by reason of the current of air and a portion of the fluid passing into the vessel, or therefrom, through the tube, whereby I am enabled to fill the vessel from an air-tight reservoir, and distribute the fluid to another air-tight reservoir, thus producing a circulation, and without any communication whatever with the atmosphere outside of the vessel.

In the accompanying drawings—

A represents the safety ventilating-vessel, made of tin and zinc combined, for the purpose of preventing oxidization.

A single tube, B, is connected to the vessel, the upper end of which is contiguous to and in direct communication with the opening through which the can is filled, while its lower end occupies a position in direct communication with the opening through which the fluid is discharged from the vessel.

The ends of the tube projecting directly into the ingress and egress-openings of the vessel, the effect of this arrangement is to produce a perfect circulation of the air and fluid from into and through the air-tight vessel or vessels, which is accomplished in a much less time than it can be done without the tube, and with perfect safety to health, life, and property.

The ingress-opening is provided with a faucet or stop-cock, C², to which the pipe leading to the reservoir is secured, and the egress-opening is likewise provided with a faucet or stop-cock, C¹, to which the pipe D, leading to the carburetter, is secured.

When the vessel is being filled, the lower stop-cock is closed, but in using it as an intermediate circulating-vessel, both of its stop-cocks are opened, and for this purpose is very useful for conducting gas, acids, and explosive fluids from one air-tight vessel to another.

The tube may be supported within the vessel by resting within the openings, or secured in position in any convenient manner.

Having described my invention,

I claim—

1. The ventilating-tube B, arranged within the vessel A, having its ends in direct communication with the ingress and egress-openings thereof, so as to facilitate the circulation of the air and fluid therein, whether in filling or discharging from or into air-tight vessels, as described.

2. The vessel A, constructed as described, to be used as an intermediate circulating-vessel, in drawing from one air-tight vessel to fill another, substantially as described.

3. The combination of the vessel A, the circulating-tube B, and the stop-cocks or faucets C¹ C², constructed, arranged, and operating as described.

LOVIAS D. TOWSLEY.
